UNITED STATES PATENT OFFICE.

BÉLA TOMKAY, OF GARY, INDIANA.

AEROPLANE TOY.

1,412,906.

Specification of Letters Patent. Patented Apr. 18, 1922.

Application filed September 1, 1921. Serial No. 497,591.

To all whom it may concern:

Be it known that I, BÉLA TOMKAY, a citizen of Hungary, residing at Gary, in the county of Lake and State of Indiana, have 5 invented certain new and useful Improvements in Aeroplane Toys, of which the following is a specification.

This invention relates generally to toys, having more particular reference to a toy 10 aeroplane adapted to be thrown into the air by a projector, the invention having for generally an object to provide a novel toy of this sort.

A further object of the invention is to 15 provide a novel arrangement by which the aeroplane is inserted into the projector with its wings and tail collapsed or folded, the same being caused to expand or unfold when released from the projector.

20 For further comprehension of the invention, and of the objects and advantages thereof, references will be had to the following description and accompanying drawings, and to the appended claims in which 25 the various novel features of the invention are more particularly set forth.

Fig. 1 of the drawings is a side view of the aeroplane as it emerges from the projector.

30 Fig. 2 is a side view of the aeroplane with wings extended.

Fig. 3 is a plan view, a portion of one of the wings being broken away to show the parts underneath.

35 Fig. 4 is a side view at right angles to Fig. 2.

Fig. 5 is a side view of the aeroplane projecting box, showing the latter in folded position.

40 Fig. 6 is a vertical sectional view of the aeroplane projecting box in extended, or operative position, this view being taken on the line 6—6 of Fig. 7.

Fig. 7 is a vertical section on the line 7—7 45 of Fig. 6 and at right angles to the latter.

Fig. 8 is a similar view to Fig. 7 but showing the plunger extended.

Referring now to Figs. 1 to 5 of the drawings, the aeroplane which I have devised to 50 be shot from the projector comprises two pairs of rigidly constructed wings 10, 10 and 11, 11 which extends at right angles to one another, the wings 10 being located at a distance above the wings 11. The wings 10 are 55 rigidly fixed on arms 12 pivoted to a horizontal bar 13 which is supported at its ends

by diagonal struts 14 extending upwardly and outwardly from a central post 15 to which the bar 13 is also rigidly connected midway between its ends. This central post 60 15 serves as the means for mounting the aeroplane on the projector, as will be presently pointed out. These arms 12 have counterweights 16 fixed thereto and acting to hold the wings in extended position. 65 When the wings are in the vertical, or folded, position shown in Fig. 1 these weights are dead centered above the bar 13. Attached at opposite ends to the inner ends of the wings 10 and the top of the post 15 are 70 comparatively light elastic cords 18.

The wings 11 are fixed on arms 20 pivoted to a bar 21 which is connected to post 15 in a like manner to the bar 13, and supported at its ends by a frame 22 mounted on the post. 75 The arms 20 have counterweights 23 fixed thereto and acting similarly to the counterweights 16. To give these wings 11 an initial movement to extended position light elastic cords 24 are attached thereto and to 80 the ends of bar 13.

Journalized in suitable brackets 26 fixed to and under the wings 11 is a pair of shafts 27 which extend diagonally with respect to the wings shown in Fig. 3. These shafts 85 27 have propellers 28 of ordinary helical construction fixed to their outer ends and are adapted to be rotated by elongated paddle wheels 29 fixed thereon under the wings 11, one side of these wheels 29 registering with 90 slots 30 cut vertically through the wings 11.

The projector from which the aeroplane is propelled comprises an elongated box 40 which may comprise two parts hinged together as at 40'. Extending longitudinally 95 in this box is a plunger 41 preferably made of two parts screwed together as at 41', one end of this plunger projecting from the upper end of the box and being provided with a socket 42 to receive the lower end of post 100 15. The inner end of the plunger 41 is secured to a crosshead 44 having projecting fingers 45 guided in slots 46 in the sides of the box 40. Secured to this crosshead 44, and to the upper end of the box 40, are 105 elastic cords 47 which constitute the propelling medium. Mounted in the lower end of the box 40 is a latch 48 adapted to engage the crosshead 44 and hold the elastic cords tensioned. This latch is of bell crank 110 shape and has an upwardly extending arm adapted to engage an eye element 50 on the

crosshead 44, the other arm of the latch projecting laterally and being adapted to be engaged by a cam disk 51 fixed on a rod 52 rotatable in the box 40 to release the latch 5 48, this rod having a knurled head 53 for rotating purposes.

In the use of the toy the plunger 41 of the projector is drawn back, and held by latch 48. The lower end of post 15 is then 10 inserted in the socket 42. When rod 52 is rotated the latch 48 is released and the plunger 41 flies outward, throwing the aeroplane up into the air. While the aeroplane is rising, the pressure of air on the wings holds the 15 latter in the folded position shown in Fig. 1 but when the aeroplane comes to rest the elastic cords and counterweights cause the wings to unfold.

As the aeroplane falls toward the ground, 20 the paddle wheels 29 are caused to rotate, driving the propellers 28, and by reason of the particular diagonal disposition of the shafts 27, causing the aeroplane to revolve around the post 15.

25 When the device is not in use the two parts of the box 40 may be folded upon one another as shown in Fig. 5, the top section of plunger 41 being first unscrewed. The box 40 is preferably of sufficient size to permit the aeroplane, when folded in Fig. 1, 30 being inserted in one of the sections of the box for convenience in carrying, a handle 60 being provided on one side of the box. The open sides of the two box halves may 35 be closed by sliding doors 61. Latches such as 62 may be provided to hold the two parts of the box 40 in either folded position.

Having thus described my invention what I claim as new and desire to protect by 40 Letters Patent of the United States is as follows:

1. A toy of the type described comprising two pairs of pivoted wings extending at right angles to one another and adapted to 45 be folded to vertical position or extended to horizontal position, means urging said wings to horizontal position, a frame element on which said wings are mounted, and a projector adapted to engage the frame 50 element, for the purpose specified.

2. A toy of the type described comprising

two pairs of pivoted wings extending at right angles to one another and adapted to be folded to vertical position or extended to horizontal position, counterweights connected to said wings to hold the same extended, said counterweights being vertically 55 dead centered with respect to the pivotal axes of the wings when the latter are folded, and elastic cords connected to the wings, for 60 the purpose specified.

3. A toy of the type described comprising a post, a pair of horizontal bars fixed at different heights to said post and extending at right angles to one another, arms pivoted 65 to the said bars, wings fixed to said arms and arranged in pairs, counterweights on said arms, and elastic cords attached to said wings, for the purpose specified.

4. In a toy aeroplane, a pair of wings, 70 propellers mounted on the wings and arranged to cause the wings to revolve as a unit around a vertical axis, and means whereby movement of air past said wings at right angles thereto, drives the said propellers.

5. In a toy aeroplane, a pair of wings, propellers mounted on the wings and arranged to cause the wings to revolve as a unit around a vertical axis, and means whereby movement of air past said wings at right angles thereto, drives the propellers, said means including shafts on which said propellers are mounted, and paddle wheels fixed 80 to said shafts.

6. In a toy aeroplane, a pair of oppositely extending wings, horizontal shafts journaled on said wings and extending diagonally thereof, propellers mounted on the outer ends of said shafts, and paddle wheels fixed 85 on said shafts.

7. In a toy aeroplane, a pair of oppositely extending wings, horizontal shafts journaled on said wings and extending diagonally thereof, propellers mounted on the outer 95 ends of said shafts, and paddle wheels fixed on said shafts, under the said wings, said wings having slots extending therethrough adjacent one side of the paddle wheels.

In testimony whereof I have affixed my 100 signature.

BÉLA TOMKAY.
